(57) CLAIM

The ornamental design for an attachable multi-article cozy wrap, as shown and described.

DESCRIPTION

FIG. 1 is a top perspective view of the attachable multi-article cozy wrap showing our new design;

FIG. 2 is a front elevational view of the attachable multi-article cozy wrap thereof;

FIG. 3 is a rear elevational view of the attachable multi-article cozy wrap thereof;

FIG. 4 is a right side elevational view of the attachable multi-article cozy wrap thereof;

FIG. 5 is a left side elevational view of the attachable multi-article cozy wrap thereof;

FIG. 6 is a top plan view of the attachable multi-article cozy wrap thereof; and,

FIG. 7 is a bottom plan view of the attachable multi-article cozy wrap thereof.

The broken lines in the drawings illustrate environmental subject matter and form no part of the claimed design.
